UNITED STATES PATENT OFFICE

ELMO JOSEPH TURMES, OF GRAND VIEW, IDAHO

HEAT RADIATOR

Application filed April 28, 1931. Serial No. 533,566.

The present invention relates to an attachment for a stove and has for its prime object to provide an economy secondary heat control unit which is exceedingly simple in its construction, inexpensive to manufacture, strong and durable, thoroughly efficient and reliable in use and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a side elevation of the apparatus embodying the features of my invention.

Figure 2 is a top plan view thereof.

Figure 3 is a horizontal section therethrough taken substantially on the line 3-3 of Figure 1.

Figure 4 is a top plan view of the stand.

Figure 5 is a vertical section taken substantially on the line 5-5 of Figure 2.

Figure 6 is a detail section taken substantially on the line 6-6 of Figure 1.

Figure 7 is a detail section taken on the line 7-7 of Figure 5, and

Figure 8 is a section taken on the line 8-8 of Figure 1.

Referring to the drawings in detail it will be seen that the numeral 5 denotes an ordinary stove such as a kitchen range or the like from which rises the stove pipe 6 in an intermediate portion of which is inserted a T-coupling 7. A damper or valve 8 is disposed in the pipe 6 above the coupling 7 and a similar damper or valve 9 is disposed in the pipe 6 below the coupling 7. A coupling 10 is at the bottom of the pipe 6 below the valve 9. Pipes 11 and 12 are connected with the T-couplings 7 and 10 respectively. The pipe 12 is longer than the pipe 11.

Numeral 14 denotes a closed drum mounted on a base or stand 15 having hollow legs 16 depending therefrom with leg extensions 17 telescopically mounted therein and adjustably held by means of setscrews 18. An elbow

19 extends through the lower portion of the side of the drum and terminates immediately above the bottom thereof. A pipe 20 rises in the drum 14 terminating immediately below the top thereof and extending through the bottom and being curved and engaged with the pipe 12. The elbow 19 is engaged with the pipe 11.

In the side of the drum 14 there is provided a clean out opening 22 having a hinged door 23 associated therewith.

From the above detailed description it will be readily apparent that the smoke, gases and the like from the stove 5, by closing the valve 9 and opening the valve 8 may be caused to pass through the pipe 12 into the drum 14 and out through the elbow 19, the pipe 11 into the pipe 6 thereby using all the heat in such gases and the like.

It is thought that the construction, utility and advantages of this invention will now be quite apparent to those skilled in this art without a more detailed description thereof.

The present embodiment of the invention has been described in detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

A heating attachment for smoke stacks comprising a pair of T-couplings adapted to be inserted in the smoke stack, a valve between said couplings, pipes extending from the T-couplings, a drum, an elbow attached to one of the pipes and extending through the side of the drum and curved downwardly terminating adjacent the bottom thereof, said other pipe rising up through the bottom of the drum and terminating adjacent the top thereof.

In testimony whereof I affix my signature.

ELMO JOSEPH TURMES.
